UNITED STATES PATENT OFFICE.

ENOS J. PETTY AND WILLIAM L. BOUCHARD, OF PORT HENRY, NEW YORK.

DEVICE FOR COMPRESSING VALVE-SPRINGS.

1,320,269.

Specification of Letters Patent. Patented Oct. 28, 1919.

Application filed May 29, 1917. Serial No. 171,797.

To all whom it may concern:

Be it known that we, ENOS J. PETTY and WILLIAM L. BOUCHARD, citizens of the United States, residing at Port Henry, in the county of Essex, and State of New York, have invented new and useful Improvements in Devices for Compressing Valve-Springs, of which the following is a specification.

This invention relates to a device which 10 may be employed to compress the springs upon the valve stems of the valves of internal combustion engines when it is desired to remove the valves from the casings therefor upon the engine cylinders.

15 The primary object of the invention is to provide a device of this character in which an arm adjustably mounted thereon is not only provided with mechanism for automatically locking the same in adjusted position, to permit the device to be used in connection with the various types of internal combustion engines now in use but also 20 serves as a support for the operating mechanism associated with a plunger for which 25 the arm serves as a guide.

A still further object of the invention is to provide a device of this character which will comprise few parts and is strong and reliable in use.

30 With these and other objects in view the invention resides in the novel combination and arrangement of parts which will be hereinafter described and particularly pointed out in the claims.

35 The preferred embodiment of the invention has been illustrated upon the accompanying drawing, although no restriction is necessarily made to the precise details of construction therein shown, as changes, alterations and modifications within the scope 40 of the appended claims may be resorted to when desired.

In the drawing:

Figure 1 is a view in side elevation partly 45 in section of a device constructed in accordance with the invention and showing the same compressing the spring upon the valve stem of a valve of an internal combustion engine.

50 Fig. 2 is an end view of the device.

Fig. 3 is a top plan view thereof, and

Fig. 4 is a detail perspective view of the spring engaging foot.

Like characters of reference denote corresponding parts throughout the various views in the drawing.

Referring now to the drawing in detail the letter A designates the portion of a cylinder of an internal combustion engine having formed thereon a valve casing B in 60 which is mounted a valve C, normally held upon its seat by a spring D encircling the stem of the valve and supported thereon by the usual pin E and washer F.

The improved device for compressing the 65 valve spring includes a bar 5 notched upon one side as at 6, for a portion of its length and provided at its lower end with a laterally extending extension 7 terminating at its free end in a flattened and tapered foot 8, 70 said foot which is adapted to be arranged between the pin E and the washer F at the lower end of the spring D has formed therein a substantially V-shaped opening 9 through which passes the stem of the valve C. The 75 upper face of the foot 8 has formed therein a centrally arranged depression 10 serving as a seat for the washer F.

Arranged above the extension 7 and in a plane parallel therewith, is an arm 11 provided at one end with a sleeve 12 through which passes the bar 5, said sleeve having passed therethrough a pin 13 normally held in one of the notches in the bar 6 by a leaf spring 14 depending from said sleeve and 80 bearing against the bar 5. The other end of the arm 11 has formed integral therewith and arranged at right angles thereto a barrel 15 through which passes a plunger 16 having a pointed lower end 17 to engage the 90 valve C. The upper end of the plunger 16 is formed with a bifurcated head 18 and has pivotally connected therewith an end of the curved plunger operating lever 19 with which are pivotally connected a pair of links 95 20 arranged upon opposite sides of the lever and fulcrumed upon the barrel 15 to permit the plunger to be reciprocated within the barrel through the operation of the lever 19.

When it is desired to employ the device 100 for compressing the valve spring upon a valve of an internal combustion engine the arm 11 is rocked against the influence of the spring 14 to disengage pin 13 from the bar 5 and permit the arm to be moved up or 105 down on said bar.

The foot 8 is now inserted between the pin E and washer F on the valve stem and the arm 11 pushed downwardly toward the extension on the bar 5, until the plunger 16 110 extends within the valve casing and bears on the valve therein, the spring 14 and pin 13

offering no resistance to the downward movement of the arm 11.

The lever 19 is now raised to cause the bar 5 to compress the valve spring D and hold 5 the same compressed until the pin has been withdrawn from the valve stem, after which the lever is released and the arm 11 moved upwardly on the bar 5 until the plunger is withdrawn from the valve casing, after 10 which the device may be laid aside until it is desired to restore the spring and pin to the valve. From the foregoing statements taken in connection with the accompanying drawing it is at once apparent that a device 15 for the purpose set forth has been provided which is highly efficient in use, although inexpensive of manufacture.

Having thus described the invention, what is claimed as new, is:—

20 1. In a device of the class described, an

arm, a plunger passing therethrough, means for operating said plunger connected therewith and with the arm, a sleeve on said arm, a bar passing through said sleeve and means for yieldingly locking said sleeve on the 25 bar.

2. In a device of the class described, an arm, a plunger carried by said arm, means for operating said plunger connected therewith and with the arm, a sleeve on said arm, 30 a bar passing through said sleeve and having notches therein, a pin passing through said sleeve, and means carried by the sleeve and engageable with said bar for yieldingly holding the pin in the notches. 35

In testimony whereof we affix our signatures.

ENOS J. PETTY.

WILLIAM L. BOUCHARD.

Copies of this patent may be obtained for five cents each, by addressing the "Commissioner of Patents.
Washington, D. C."

It is hereby certified that the name of the first-mentioned patentee in Letters Patent No. 1,320,269, granted October 28, 1919, for an improvement in "Devices for Compressing Valve-Springs," was erroneously written and printed as "Enos J. Petty," whereas said name should have been written and printed as *Erros J. Petty*; and that the said Letters Patent should be read with this correction therein that the same may conform to the record of the case in the Patent Office.

Signed and sealed this 10th day of February, A. D., 1920.

[SEAL.]

M. H. COULSTON,

Acting Commissioner of Patents.
